UNITED STATES PATENT OFFICE

RALEIGH B. BUZZAIRD, OF WASHINGTON, DISTRICT OF COLUMBIA

DESIGN FOR A SHEET OF PAPER

Application filed February 28, 1931. Serial No. 38,876. Term of patent 3½ years.

To all whom it may concern:

Be it known that I, RALEIGH B. BUZZAIRD, a citizen of the United States, residing at Washington, in the District of Columbia, have invented a new, original, and ornamental Design for a Sheet of Paper, of which the following is a specification, reference being had to the accompanying drawing, forming part thereof.

The figure is a face view of a sheet of paper showing my new design.

I claim:

The ornamental design for a sheet of paper substantially as shown.

RALEIGH B. BUZZAIRD.
